United States Patent Office.

EDWIN FERNALD, OF TURNER, MAINE.

Letters Patent No. 80,344, dated July 28, 1868.

IMPROVED DEVICE FOR HOLDING TOOLS AGAINST GRINDSTONES.

The Schedule referred to in these Letters Patent and making part of the same.

TO ALL WHOM IT MAY CONCERN:

Be it known that I, EDWIN FERNALD, of Turner, in the county of Androscoggin, and State of Maine, have invented a new and improved Device for Holding Tools against Grindstones; and I do hereby declare that the following is a full, clear, and exact description thereof, which will enable those skilled in the art to make and use the same, reference being had to the accompanying drawings, forming part of this specification, in which—

Figure 1 represents a vertical longitudinal section of my improved machine, the plane of section being indicated by the line $x x$, fig. 2.

Figure 2 is a plan or top view of the same.

Similar letters of reference indicate corresponding parts.

This invention relates to a device by which tools having a long cutting-edge can be held against grindstones, and can be sharpened, the device being so arranged that the bevel formed on the tool will be entirely uniform, and that its edge will be ground perfectly straight.

The invention consists in the use of a shoe or clamp, which slides on a horizontal rod, and which is moved thereon by means of chains passing over pulleys in the end of a stationary frame.

In the front end of this shoe the tool to be ground is secured, and by moving the shoe on the said horizontal rod the tool will be drawn across the edge of the grindstone. The front part of the shoe rests upon an adjustable support, the length of which is regulated by a screw, so that by turning the said screw the tool can be brought as close as necessary against the grindstone.

A represents a bench, which is standing upon legs, B, and in which the bearings for the shaft of the grindstone C are arranged.

D is a vertical frame, consisting of the uprights $a a$, at the sides of the bottom plate b , and of the upper brace or plate c . This frame is set upon the bench A, and is secured to the same by a screw or screws and nuts, d , passing through the bottom, b , of the frame D, and through a plate, e , which is arranged on the under side of the bench, as is clearly shown in fig. 1.

By loosening the nut on the bolts d the frame D can be moved nearer to or further from the axis of the grindstone, and be fastened in any desired position.

It will be seen that the frame D, or rather its top and bottom plates, are arranged parallel with the axis of the grindstone C.

E is a horizontal metal rod, arranged between the side pieces of the frame D.

F is a clamp or shoe, which has two legs on its under side, near its rear end, by which it is fitted upon and around the rod E, so as to slide and turn thereon. Two chains, $f f$, which are secured to a drum, g , on the upper plate c of the frame D, and to the shoe F, and which pass over pulleys, h , which are fixed to the sides of the frame D, serve to move the shoe on the rod E, whenever the drum g is turned by means of a crank, i , as shown.

G is a horizontal rail, arranged on or near the front part of the bed-plate b . H is a jointed rod which fits through a mortise in the shoe, and which is provided with a wheel, j , on its lower end, which wheel fits into or upon the rail G, as shown. I is a vertical screw which fits through a nut, R , which is elevated by braces, l , above the surface of the shoe. The lower end of this screw fits upon the upper end of the jointed rod H. By turning the screw, so that the distance between the rail and nut is diminished or increased, the front edge of the shoe, and with it the tool held therein, will be lowered or raised, as may be desired.

The tool is held in a recess, or between jaws in the front part of the shoe, and is clamped by means of set-screws $m m$, as is clearly shown in the drawing.

When the tool is clamped, the screw T is adjusted to regulate how much of the tool should be ground off; then the crank i is turned, and the edge of the tool is drawn across that of the grindstone.

I am aware that tools are already held in levers, which are moved so as to draw the edge of the tool over the stone, but these levers can never be moved as steady as the shoe F is moved by the chains ff .

Furthermore, these levers could not be steadied in front, and consequently the straight edge of the tool could only be obtained by the ability and skill of the operator, while, by the use of my machine, a perfectly-straight and smoothly-bevelled edge must result as long as the whole length of the tool is drawn across the face of the stone.

Claim.

I claim as new, and desire to secure by Letters Patent—

The vertically-adjustable jointed bar H, bearing the wheel j, in combination with the guide G and horizontally-travelling shoe F, as herein described for the purpose specified.

EDWIN FERNALD.
